[57] **CLAIM**

The design for a cylindrical eraser, as shown and described.

DESCRIPTION

FIG. 1 is a top perspective view of a cylindrical eraser showing my new design, the writing instrument depicted by means of broken lines being for illustrative purposes only and forming no part of the claimed design;

FIG. 2 is a top plan view of an eraser;

FIG. 3 is a side elevational view thereof, all other sides being identical thereto; and,

FIG. 4 is a bottom view thereof.
